Primary Examiner — Stella Reid*Assistant Examiner* — Keli L Hill(74) *Attorney, Agent, or Firm* — Antoinette G. Giugliano, PC; AGG Intellectual Property Law(57) **CLAIM**

The ornamental design for an animal shaped shoe, as shown and described.

DESCRIPTION

FIG. 1 is a side view of an animal shaped shoe, embodying my new design;

FIG. 2 is the other side view thereof;

FIG. 3 is a bottom view thereof;

FIG. 4 is a top view thereof;

FIG. 5 is a front view thereof; and,

FIG. 6 is a back view thereof.

The portions of the animal shaped shoe shown in broken lines form no part of the claimed design.
